UNITED STATES PATENT OFFICE.

CHARLES HAMMEN, OF CHICAGO, ILLINOIS, ASSIGNOR OF ONE-HALF TO ELWYN W. SEYMOUR, OF EVANSTON, ILLINOIS.

CONVERTIBLE ELEVATOR.

1,193,893.

Specification of Letters Patent.

Patented Aug. 8, 1916.

Application filed July 23, 1915. Serial No. 41,466.

To all whom it may concern:

Be it known that I, CHARLES HAMMEN, a citizen of the United States, residing at Chicago, in the county of Cook and State of Illinois, have invented new and useful Improvements in Convertible Elevators, of which the following is a specification, reference being had to the accompanying drawings, forming a part thereof.

10 The purpose of this invention is to provide a pair of elevator cars, together with suitable lifting gear for them, so arranged that the two cars may be operated in unison as a single large elevator, but adapted 15 to permit separate operation of the cars at will as hereinafter described.

The invention consists in this combination together with certain features and elements of construction described and shown in the 20 drawings, as indicated by the appended claims.

In the drawings: Figure 1 is a side elevation of the two elevator cars and their lifting gear showing the cars arranged to 25 operate in unison. Fig. 2 is an end elevation of the parts shown in Fig. 1. Fig. 3 is an enlarged detail view partly in section showing the construction of the winding drum. Fig. 4 is a view taken similarly to 30 Fig. 1 showing the two cars arranged for simultaneous operation in opposite directions counterbalancing each other. Fig. 5 is a view taken similarly to Fig. 1 showing the cars arranged for simultaneous operation 35 in opposite directions and through different distances. Fig. 6 is a detail plan view of a modified form of lifting gear. Fig. 7 is a detail section illustrating a bridging apron and a coupling link.

40 The elevator combination which is the subject of this invention is designed for situations where there is occasional demand for an elevator of unusually large capacity, as for handling an automobile or a similarly 45 bulky load, but where ordinarily a pair of smaller sized elevator cars will serve most purposes.

The drawings show two platform elevator cars, A and B, respectively, mounted to 50 travel adjacent and parallel to each other, and in this instance arranged to serve three

floors or landings, C, D and E, respectively. In each of the cars the floor or platform is suspended from a frame comprising side members, F¹, side braces, F², and an overhead cross bar, F³; it will be seen that this frame is connected only at two opposite sides to the floor platform leaving the other two sides clear for access in loading and unloading. It may be further noted that 55 the clear side A¹ of the car, A, is thus brought adjacent to the clear side, B¹, of the car, B, while the opposite clear sides, A² and B², respectively, will register with the landing floors, C, D and E. Thus when the 60 two platforms are brought to a common plane they provide a clear floor space from A² to B², and if operated in unison will serve practically as a single large elevator.

To secure lightness of construction each 70 car is supported by two cables, G¹ and G², connected respectively to the two side frames, F¹, F², of the car, and passing over sheaves or head pulleys, H¹ and H², and thence to the winding drum. Except in the 75 modification shown in Fig. 6, the winding drums for both cars, A and B, are carried on a single shaft, J, driven from a power shaft, K, through a worm gear, L. Two drums, A^x and A^y, and B^x and B^y, are shown 80 for each of the cars, A and B. In the arrangement illustrated in Fig. 1 the hoisting cables for both cars are wound on the smaller drums, A^x and B^x, and since both these drums are rigid with the shaft, J, it will 85 be seen that the two cars will be operated simultaneously at exactly the same speed, so that with the cables leading off the same side of both drums, A^x and B^x, the cars will operate in the same direction simultaneously and maintain their alinement with 90 each other so as to serve in unison. For this arrangement there is provided no counterbalance for the cars and this is the principal reason for leading the hoisting cables 95 on to the smaller drums. During such use the short gap between the edges, A¹ and B¹, of the two cars may be bridged by a thin metal apron, M, shown in detail in Fig. 7 as hinged at M¹, to the car, A, and adapted when out 100 of use to be folded back upon the floor of said car. As a precaution against the break-

ing of the cables of one car, the platforms, A and B, may be connected together as by the coupling link, N, (see Fig. 7), so that in case of such breakage the injured car will 5 be restrained by its connection to the other car and will not drop to the bottom of the shaft.

When the smaller drums, A^x and B^x , are in use the larger drums, A^y and B^y , are temporarily supported to one side of the smaller drums and out of contact with the shaft, J, in any suitable manner, as by the cradle plates, O, and braces, P, shown in Fig. 3. But when the cars are operated separately, 15 it will be obvious that if they are also operated in opposite directions, so that one goes up as the other goes down with the hoisting cables oppositely wound on the drums, the weight of one car will serve to counter- 20 balance the weight of the other, and the dead weight of the cars themselves is thus eliminated as a part of the load on the engine permitting operation at a higher speed. For this purpose therefore the larger drums, 25 A^y and B^y , are brought into service. This is done by shifting the larger drums into a position in which they encircle the smaller drums and in which they are secured by bolting their annular flanges, Y^1 , to the 30 flanges, X^1 , of the smaller drums by bolts, Z, indicated in Fig. 3. The hoisting cables are unwound from the smaller drums and wound onto the larger drums, one of the elevator cars being blocked meanwhile in registration 35 with the landing, E, while the other car stands at its lower limit of travel in registration with the floor, C.

As indicated in Fig. 4, the cables of the respective cars, A and B, are arranged to 40 lead off from opposite sides of the drums, A^y and B^y , respectively, so that both drums being fast on the same shaft, J, the cars will travel in opposite directions when the power is applied. To insure safety with such operation, it is desirable to mount a partition 45 between the two cars so that the load on either of them may not project over the adjacent edges, A^1 or B^1 , and be damaged by collision with the other car in passing it. 50 Parallel rails, Q and R, extending vertically at both sides of the shaft provide a groove in which a wall of boards or other suitable material may be inserted to form such a partition wall at S; when the two cars are 55 to be operated in unison, as in Fig. 1, this wall may be readily removed leaving the space clear between the cars.

A third arrangement which is possible with the combination shown is that illustrated in Fig. 5, in which the two cars are 60 operated simultaneously and in opposite directions, but in which the car, A, has its hoisting cables attached to the smaller drums, A^x , while the cables of the car, B,

are wound onto the larger drum, B^y ; if the 65 diameters of the drums, A^x and B^y , are in the ratio of one to two, it will be evident that the car, A, will travel only half as far as the car, B, for a given number of turns of the shaft, J, to which both drums are 70 rigidly secured. Thus the car, A, may be made to travel only between the floors, D and E, while the car, B, may travel between the floors B and E, without stopping at the floor, D, so that the loads may be distributed 75 to the two cars in accordance with their destination whether it be the floor D or the floor C, assuming the upper floor, E, as the loading position, or in accordance with their source if they are being unloaded from the 80 floors, D and C, and elevated to the floor, E. This arrangement has been found of peculiar value in a ship's elevator, in which, C, may represent the bottom floor of the ship's hold while, E, indicates the loading floor 85 from which the gangway leads to the wharf, while, D, may be a permanent or a removable mezzanine floor in the hold. It will be seen that with the two cars connected respectively to the different sized drums, A^x 90 and B^y , as in Fig. 5, they will not completely counterbalance each other, but if operated in opposite directions, as indicated by the opposite windings of the cables, their dead load will be partially compensated 95 thus to some extent lightening the load on the engine or motor which operates them.

Fig. 6 illustrates a hoisting gear for a pair of elevator cars as above described, and designed to accomplish the same result as 100 the double-drum system, but avoiding the detachment and reattachment of the hoisting cables in shifting from one mode of operation to the other. In this arrangement, the engine or motor is connected to a side shaft 105 instead of to the drum shaft, J, and the latter is made in two separate parts, J^1 and J^2 , carrying respectively the winding drums, U and V. For moving the two cars in unison, as in the arrangement of Fig. 1, 110 the power shaft, T, is connected with the two drums, U and V, through two pairs of two to one gears, 1 and 2, and 3 and 4, respectively, and with both cables leading from the same side of the two drums it will 115 be evident that the two cars will move together as desired.

Associated with the gear, 1, is a gear, 5, and rigid with the shaft, J^1 , is a gear, 6, equal in size to the gear, 5. The shaft, J^2 , 120 carries a gear, 7, equal in size to the gear, 3, while an idler gear, 8, is mounted in position to mesh constantly with the gear, 7. Now for obtaining the operation indicated in Fig. 4, the gears, 1, 5 and 3, which are splined 125 onto the shaft, T, or shifted longitudinally thereon to bring the gear, 5, into mesh with the gear, 6, and to move the gear, 3, into

- mesh with the gear, 8. When the power is applied to the shaft, T, the two drums, U and V, will be rotated at equal speeds in opposite directions by reason of the presence of the reversing idler, 8, in the train. Either of the slideable gears on the shaft, T, may be removed to an idle position out of mesh with the gears on the drum shaft for making the above change. Starting with both cars at the lower limit, C, the gear, 3, is first moved to idle position and the power employed for lifting the car, A, to its upper limit at which it may be blocked while the gear, 5, is then shifted to mesh with gear, 6, and gear, 3, is shifted to mesh with gear, 6, and gear, 3, is moved on into registration with the reversing idler, 8. Then removing the blocking and connecting the power the cars will travel oppositely without any change in the cable winding on either drum.
- Now to secure the third mode of operation, as indicated in Fig. 5, it is only necessary to shift the associated gears, 1 and 5, back to their original position in which the gear, 1, meshes with the gear, 2, so that while the drums, U and V, are rotated in opposite directions the drum, U, will turn at only one-half the speed of the drum, V,— in other words, the travel on the elevator connected to the drum, U, will be only half that of the car connected to the drum, V. Fig. 6 is more or less diagrammatic and it may be understood that any suitable means for shifting the gears on the shaft, T, and for retaining them in their various positions may be provided.
- I claim:—
1. The combination of a plurality of platform elevator cars mounted for travel side by side, and hoisting gear adapted for moving said cars in unison with their platforms substantially aligned in a common plane.
  2. The combination of a plurality of platform elevator cars mounted for travel side by side, the adjacent sides of said cars being clear for access from one car to another, and hoisting gear adapted for moving said cars in unison with their platforms substantially aligned in a common plane.
  3. The combination of a plurality of platform elevator cars mounted for travel side by side, the adjacent sides of said cars being clear for access from one car to another, the opposite side of one car being clear for access to a landing, together with hoisting gear adapted for moving said cars in unison with their platforms substantially aligned in a common plane.
  4. In combination with a pair of platform elevator cars mounted for travel side by side, hoisting apparatus for both cars and means for synchronizing said apparatus to secure simultaneous movement of the cars in definite relation to each other, such hoisting apparatus for one of the cars including a connection reversible at will 65 adapted to cause travel of the cars in the same or in opposite directions simultaneously as desired.
  5. In combination with a pair of platform elevator cars mounted for travel side by side, hoisting apparatus for both cars and means for synchronizing said apparatus to secure simultaneous movement of the cars, such apparatus including means for varying the speed ratio between said cars 70 at will for causing them to travel equal or different distances simultaneously as desired.
  6. In combination with a pair of platform elevator cars mounted for travel side by side, a common power shaft and positive connections therefrom to both cars for moving them simultaneously, the connection for one car being reversible at will to permit said cars to be operated in unison or in 80 counterbalancing relation as desired.
  7. In combination with a pair of platform elevator cars mounted for travel side by side, a common power shaft and positive connections therefrom to both cars for moving them simultaneously, the connection for one car including means for varying the speed ratio between said car and the shaft adapted to permit the cars to travel equal or different distances simultaneously.
  8. In combination with a pair of platform elevator cars mounted for travel side by side, the adjacent sides of said cars being clear for access from one car to the other, hoisting apparatus for both cars and means 90 for synchronizing said apparatus for moving the cars in unison, such hoisting apparatus for one of the cars including a connection reversible at will adapted to permit simultaneous travel of the cars in opposite 100 directions when desired, said cars being mounted to leave a clearance space between their said adjacent sides, a partition wall, and means for removably supporting said wall in said clearance space.
  9. In combination with a pair of platform elevator cars mounted for travel side by side, the adjacent sides of said cars being clear for access from one car to the other, hoisting apparatus for both cars and means 110 for synchronizing said apparatus for moving the cars in unison, such hoisting apparatus for one of the cars including a connection reversible at will adapted to permit simultaneous travel of the cars in opposite 120 directions when desired, said cars being mounted to leave a clearance space between their said adjacent sides, and an apron adjustably carried by one of the cars adapted for bridging said clearance space when the 125 cars are operated in unison.
  10. In combination with a pair of platform elevator cars mounted for travel side

by side, the adjacent sides of said cars being clear for access from one car to the other, hoisting apparatus for both cars and means for synchronizing said apparatus to cause the cars to operate in unison, together with a coupling link connecting said cars at their adjacent sides as and for the purposes described.

In testimony whereof I have hereunto set my hand at Chicago, Illinois, this 15th day ¹⁰ of July, 1915.

CHARLES HAMMEN.
